DISPENSER FOR SELF-ADHESIVE TAPE

William Harry Denkin, Ealing, London, England,
assignor to Rexel Products of Canada Limited,
Toronto, Canada

Application December 28, 1950, Serial No. 203,103
In Great Britain November 21, 1950

9 Claims. (Cl. 242—55.5)

1

The subject matter of this invention is a one piece plastic dispenser of the type adapted to utilize a pressure sensitive roll tape. One object of the invention is realized in the provision of an effective and simplified dispenser of the character referred to wherein the shell thereof has one upstanding side only and this wall embodies a peripheral transversely arranged inwardly overhanging and rearwardly and downwardly flared rim characterizing in part a top wall of the shell and in part an advantageous back rest for the palm of the hand of the operator using the dispenser, the back rest being merged with a transversely arranged bottom wall of the shell extending from the side wall and adapted when the dispenser is used to be conveniently seated on the middle fingers of the hand of the operator or on an appropriate supporting surface when the dispenser is not in use. Specifically another object resides in arranging the overhanging rim to the rear of a disc shaped part of the unitary and upstanding side wall which carries a centrally arranged tubular portion comprising a resilient and normally retracted finger having a radially but outwardly extending locking lip or terminal adapted to be actuated by the roll of tape when moved into or out of the shell and concomitantly on or off the tubular portion. Another object is predicated upon serviceable and effective means for anchoring tape unwound from the roll on an upwardly flared portion inwardly overhanging the front inclined wall of the shell, the front wall being merged with the unitary upstanding side wall and with the bottom wall or base of the shell, thus precluding buckling of the side wall. Other important objects and functional and structural features and advantages of the invention will appear from the following detailed description considered in the light of the accompanying drawings wherein.

Fig. 1 is a perspective view of the dispenser according to my invention.

Fig. 2 is a side elevational view of Fig. 1, illustrating the open side face of the dispenser and a roll of pressure sensitive or self adhesive tape rotatably mounted therein.

Fig. 3 is another elevational view of Fig. 1 but showing the closed side face of the dispenser.

Fig. 4 is a rear elevational view on the line 4—4 of Fig. 2, however with the roll of tape omitted.

Fig. 5 is a front elevational view of the dispenser taken on the line 5—5 of Fig. 2 but with the roll of tape omitted to depict the locking member or finger.

2

Fig. 6 is a plan view of Fig. 3, showing the dispenser held within one hand of the operator thereof, and

Fig. 7 is a sectional view on the line 7—7 of Fig. 2.

According to the invention, the dispenser is in the form of a one piece open plastic shell, generally designated SH, having the bottom substantially rectilinear wall 2, constituting a base for the shell and adapted to be seated on a suitable supporting surface SF. The side wall 1 is integral or merged with bottom wall 2 and is disposed at a right angular relation or normal thereto. The front inclined wall 3 is integral or merged with bottom wall 2 and side wall 1 and is disposed at right angles or normal thereto. Tubular portion 5 has its inner end merged with side wall 1 and has a free unsupported outer end E spaced from bottom wall 2 and disposed to the rear of reentrant gap R dividing side wall 1 into front and rear components FC and RC respectively (Figs. 1, 2 and 3).

Tubular portion 5 as shown is cylindrical and is arranged substantially centrally of the rear component RC, the forward portion of the latter may be considered for purposes of specification as a disc shaped section having the crown portion D. To the rear of this section is the rearwardly flared or expanding flange or rim, broadly indicated F, interrupted intermediately thereof by notch N. This rim is arranged at the periphery of the rear component RC or transversely thereto. Rim F may be said to be partly tapered and in part constitutes the top wall TW and in part the rear wall or back rest BR of the plastic shell SH. Of course rim F is integral or merged with base 2 and the side wall 1.

As illustrated spaced slits 7 interrupt the body of the tubular portion 5 and lead to the free unsupported outer end E. Lip or terminal 9 extends radially outwardly, that is, laterally of the resilient finger or member 8 straddled by slits 7. Lip 9 removably holds the roll of tape TP on the tubular portion 5 contiguous to side wall 1 as is well understood. The upwardly flared portion or ledge EP at the upper end of the front inclined wall 3 of shell SH embodies an anterior toothed face TF and a posterior flat face FF (Fig. 1).

The dispenser in accordance with my invention has one side wall only, namely, side wall 1. Hence the shell of the dispenser opposite the upstanding side 1 is always open for prompt removal or reception of the roll of tape off or on the tubular portion 5. The peripheral transversely arranged rim F, that is, the lower part BR there-

of constitutes a rest for the palm of the hand of the operator when holding the dispenser. More specifically, the inclined wall 3, the bottom wall or base 2 and the transversely arranged peripheral rim F constitute a fully open side face of the shell and this open side face extends the entire length and height of the shell and is opposite to the upstanding side wall 1. Through this open side face it is apparent that the roll of tape TP can be readily and promptly inserted into or removed from the shell and concomitantly on or off the tubular portion 5 at which time the roll actuates or abuts lip 9 flexing the resilient member inwardly to release or unlock the roll, that is, resilient member or finger 8 is normally flush with tubular portion 5. In other words finger 8 is held normally retracted to be flush with tubular portion 5. Of course by manually pressing lip 9 inwardly, the reel or roll of tape can be quickly slipped or mounted over tubular portion 5. Also due to the inherent operation of the resilient finger 8 the roll may be placed over lip 9 to automatically press finger 8 inwardly prior to shifting the roll over tubular portion 5. In either case after the roll is completely seated on and about tubular portion 5, the resilient finger 8 snaps back or retracts automatically. This operation is inherent. In addition if the roll of tape be on tubular portion 5, this roll of tape if desired may also be conveniently employed to automatically actuate to depress finger 8. In this connection, the roll or reel is first manually grasped by the fingers of the operator, who thereafter simply pulls the roll towards lip 9 and the latter is depressed as the roll is pulled off tubular portion 5. This function is likewise inherent in the structural organization herein specifically described and shown.

It should be observed that top wall TW progressively increases in width in proportion to its distance away from the disc shaped portion D. Roll of tape TP is preferably of the pressure sensitive or self adhesive type and an end thereof as T may be readily unwound and fastened on the flat face FF and severed by the toothed face TF as is well understood. The roll of tape of course is rotatably guided on the tubular portion 5 while the front forwardly and upwardly inclined wall 3, apart from carrying the inwardly overhanging and upwardly flared portion FP, integrally interconnects, that is, it is merged with base 2 and unitary upstanding side wall 1, thus precluded buckling of the latter relative to base 2. Similarly back rest BR serves a like function in that it interconnects side wall 1 and base 2.

While the above is a description of the principles of this invention in connection with the specific dispenser illustrated, it is to be clearly understood that this description in the light of such illustrations is made only by way of example and not as a limitation on the scope of the invention as defined in the accompanying claims.

I claim:

1. A dispenser adapted to removably receive a roll of self-adhesive tape; comprising, an open one piece shell embodying a bottom wall adapted to be seated on a supporting surface and having a forwardly arranged inclined front wall extending upwardly and outwardly relative to said bottom wall and merged therewith, said shell having one side wall only, said side wall being substantially normal to said bottom wall and to said inclined wall and integral with both of said last mentioned walls, said side wall having a

reentrant gap near the front part thereof, a tubular portion substantially normal to said side wall and extending transversely of and within said shell and spaced from said bottom wall and having its inner end spaced from and disposed to the rear of said gap and merged with said side wall and having a free unsupported outer end, said tubular portion having spaced slits leading to and interrupting said unsupported outer end and defining a resilient member, said tubular portion adapted to rotatably support said roll and said resilient member having a lip projecting outwardly and laterally thereof and beyond said unsupported outer end to disengageably cooperate with said roll to hold the latter on said tubular portion and contiguous to said side wall, and the forward part of said inclined wall including a ledge at its upper end, said ledge having a posterior portion to which tape unwound from said roll may be adhesively secured and having an anterior toothed portion to facilitate severing of said tape when unwound from said roll, said shell having an open side face extending across the length and height of said shell and disposed opposite to said side wall for convenient insertion or removal of said roll into or out of said shell and concomitantly on or off said tubular portion pursuant to automatic actuation of said lip by said roll to flex said resilient member in a direction towards the inside of said tubular portion.

2. A dispenser adapted to removably receive a roll of self-adhesive tape; comprising, an open one piece shell embodying a substantially rectilinear bottom wall adapted to be seated on a supporting surface and having a forwardly arranged inclined front wall extending upwardly and outwardly relative to said bottom wall and merged therewith, said shell having one side wall only, said side wall being substantially normal to said bottom wall and to said inclined wall and integral with both of said last mentioned walls, said side wall having a reentrant gap near the forward part thereof and in part dividing said side wall into front and rear components, a tubular portion substantially normal to said rear component and extending transversely of and within said shell and spaced from said bottom wall and having its inner end spaced from and to the rear of said gap and merged with said rear component and having a free unsupported outer end, said tubular portion having spaced slits leading to and interrupting said unsupported outer end and defining a resilient member, said tubular portion adapted to rotatably support said roll and said resilient member having a lip projecting outwardly and laterally thereof and beyond said outer end to disengageably cooperate with said roll to hold the latter on said tubular portion and contiguous to said rear component, and the forward part of said inclined wall including a ledge at its upper end, said ledge having a posterior portion to which tape unwound from said roll may be adhesively secured and having an anterior toothed portion to facilitate severing of said tape when unwound from said roll, said shell having an open side face extending across the length and height of said shell and disposed opposite to said side wall for convenient insertion or removal of said roll into or out of said shell and concomitantly on or off said tubular portion pursuant to automatic actuation of said lip by said roll to flex said resilient member in a direction towards the inside of said tubular portion.

3. A dispenser adapted to removably receive a roll of self-adhesive tape; comprising, an open one piece plastic shell embodying a bottom wall adapted to be seated on a supporting surface and having a forwardly arranged inclined front wall extending upwardly and outwardly relative to said bottom wall and merged therewith, said shell having one side wall only, said side wall being substantially normal to said bottom wall and to said inclined wall and integral with both of said last mentioned walls, said side wall having a re-entrant gap near the forward part thereof and in part dividing said side wall into front and rear components, a cylindrical tubular portion substantially normal to said rear component and extending transversely of and within said shell and spaced from said bottom wall and having its inner end spaced from and disposed to the rear of said gap and merged with said rear component and having a free unsupported outer end, said tubular portion having spaced slits leading to and interrupting said outer end and defining a resilient member, said tubular portion adapted to rotatably support said roll and said resilient member having a lip projecting outwardly and laterally thereof and disposed radially beyond said unsupported outer end to disengageably cooperate with said roll to hold the latter on said tubular portion and contiguous to said side wall, and the forward part of said inclined wall including an upwardly flared ledge at its upper end integral with said front component and inwardly overhanging said inclined wall, said ledge having a posterior portion to which tape unwound from said roll may be adhesively secured and having an anterior toothed portion to facilitate severing of said tape when unwound from said roll, said shell having an open side face extending across the length and height of said shell and disposed opposite to said side wall to permit insertion or removal of said roll into or out of said shell and concomitantly on or off said tubular portion pursuant to automatic actuation of said lip by said roll to flex said resilient member in a direction towards the inside of said tubular portion.

4. A dispenser adapted to removably receive a roll of self-adhesive tape; comprising, an open one piece shell embodying a bottom wall adapted to be seated on a supporting surface and having a forwardly arranged inclined front wall extending upwardly and outwardly relative to said bottom wall and merged therewith, said shell having one side wall only, said side wall being substantially normal to said bottom wall and to said inclined wall and integral with both of said last mentioned walls, said side wall having a re-entrant gap near the forward part thereof and in part dividing said side wall into front and rear components, a tubular portion substantially normal to said rear component and extending transversely of and within said shell and spaced from said bottom wall and having its inner end spaced from and disposed to the rear of said gap and merged with said rear component and having a free unsupported outer end, said tubular portion having spaced slits leading to and interrupting said outer end and defining a resilient member, said tubular portion adapted to rotatably support said roll and said resilient member having a lip projecting outwardly and laterally thereof and beyond said unsupported outer end to disengageably cooperate with said roll to hold the latter on said tubular portion and contiguous to said side wall, the forward part of said inclined wall

wall including an upwardly flared ledge at its upper end integral with said front component and overhanging said inclined wall, said ledge having a posterior portion to which tape unwound from said roll may be adhesively secured and having an anterior toothed portion to facilitate severing of said tape when unwound from said roll, said rear component having an upper arcuate crown portion defining in part a forwardly disposed disk shaped section, and a transversely arranged peripheral rim at the rear of said section and substantially normal to and integral with said crown portion and the lower part of said rear component and merged with and extending upwardly from said bottom wall, said shell having an open side face extending across the length and height of said shell and disposed opposite to said side wall for convenient insertion or removal of said roll into or out of said shell and concomitantly on or off said tubular portion pursuant to automatic actuation of said lip by said roll to flex said resilient member in a direction towards the inside of said tubular portion.

25 5. A dispenser adapted to removably receive a roll of self-adhesive tape; comprising, an open one piece shell embodying a transversely arranged bottom wall adapted to be seated on a supporting surface and having a forwardly arranged inclined front wall extending outwardly relative to said bottom wall and merged therewith; said shell having one side wall only, said side wall being substantially normal to said bottom wall and to said inclined wall and integral with both of said last mentioned walls, said side wall having a re-entrant gap near the forward part thereof and in part dividing said side wall into front and rear components, a tubular portion substantially normal to said rear component and extending transversely of and within said shell and spaced from said bottom wall and having its inner end spaced from and disposed to the rear of said gap and merged with said rear component and having a free unsupported outer end, said tubular portion having spaced slits leading to and interrupting said outer end and defining a resilient member, said tubular portion adapted to rotatably support said roll and said resilient member having a lip projecting outwardly and laterally thereof and beyond said outer end to disengageably cooperate with said roll to hold the latter on said tubular portion and contiguous to said side wall, the forward part of said inclined wall including an upwardly flared ledge at its upper end integral with said front component and overhanging said inclined wall, said ledge having a posterior portion to which tape unwound from said roll may be adhesively secured and having an anterior toothed portion to facilitate severing of said tape when unwound from said roll; said rear component having an upper arcuate crown portion defining in part a forwardly disposed disk shaped section, and a transversely arranged peripheral rim at the rear of said section and substantially normal to and integral with said crown portion and the lower part of said rear component and merged with and extending upwardly from said bottom wall, said rim in part constituting the top wall of said shell and progressively increasing in width in proportion to its distance away from the rear part of said section and in part overhanging said rear component and roll; said inclined wall, bottom wall and rim defining an open side face extending across the length and height of said shell and opposite to said side wall for

convenient insertion or removal of said roll into or out of said shell and concomitantly on or off said tubular portion pursuant to automatic actuation of said lip by said roll to flex said resilient member in a direction towards the inside of said tubular portion.

6. A dispenser adapted to removably receive a roll of self-adhesive tape; comprising, an open one piece shell embodying a substantially rectilinear bottom wall constituting a transversely arranged base adapted to be seated on a supporting surface and having a forwardly arranged inclined front wall extending upwardly and outwardly relative to said bottom wall and merged therewith, said shell having one side wall only, said side wall being substantially normal to said bottom wall and to said inclined wall and integral with both of said last mentioned walls, said side wall having a reentrant gap near the forward part thereof and in part dividing said side wall into front and rear components, a cylindrical tubular portion substantially normal to said rear component and extending transversely of and within said shell and spaced from said bottom wall and having its inner end spaced from and disposed to the rear of said gap and merged with said rear component and having a free unsupported outer end, said tubular portion having spaced slits leading to and interrupting said outer end and defining a resilient member, said tubular portion adapted to rotatably support said roll and said resilient member having a lip adapted to be actuated by said roll and projecting outwardly and radially beyond said unsupported outer end to disengageably cooperate with said roll to hold the latter on said tubular portion and contiguous to said side wall, the forward part of said inclined wall including an upwardly flared ledge at its upper end integral with said front component and inwardly overhanging said inclined wall, said ledge having a posterior portion to which tape unwound from said roll may be adhesively secured and having an anterior toothed portion to facilitate severing of said tape when unwound from said roll, said rear component having an upper arcuate crown portion defining in part a forwardly disposed disk shaped section, and a transversely arranged peripheral rim at the rear of said section and substantially normal to and integral with said crown portion and the lower part of said rear component and merged with and extending upwardly from said bottom wall, said rim in part constituting the top wall of said shell and progressively increasing in width in proportion to its distance away from the rear part of said section and in part overhanging said rear component and roll, said rim embodying a reentrant notch and said tubular portion being disposed substantially centrally of said rear component; said front wall, bottom wall and rim defining an open side face extending across said shell opposite to said side wall for convenient insertion or removal of said roll into or out of said shell and concomitantly on or off said tubular portion pursuant to automatic actuation of said lip by said roll to flex said resilient member in a direction towards the inside of said tubular portion.

7. A dispenser adapted to removably receive a roll of self adhesive tape; comprising, an open one piece plastic shell embodying a bottom wall constituting a transversely arranged base adapted to be seated on a supporting surface and having a transversely arranged front wall, said shell having one side wall only, said side wall being

substantially normal to said base and front wall, said side wall having a reentrant gap near the forward part thereof and in part dividing said side wall into front and rear components, a cylindrical tubular portion substantially normal to said rear component and extending transversely of and within said shell and spaced from said base and having its inner end spaced from and disposed to the rear of said gap and having a free unsupported outer end, said tubular portion having spaced slits leading to and interrupting said outer end and defining a resilient member, said tubular portion adapted to rotatably support said roll and said resilient member having a terminal lip adapted to be actuated by said roll and projecting outwardly and radially beyond said unsupported outer end to disengageably cooperate with said roll to hold the latter on said tubular portion and contiguous to said side wall, and the forward part of said front wall including an accessible ledge having a posterior portion to which tape unwound from said roll may be adhesively secured and having an anterior toothed portion to facilitate severing of said tape when unwound from said roll, said shell having a transversely arranged rim merged with said rear component and in part adapted to overhang said roll; said base, front wall and rim defining an open side face extending across the length and height of said shell and opposite to said side wall for convenient insertion or removal of said roll into or out of said shell and concomitantly on or off said tubular portion pursuant to automatic actuation of said lip by said roll to flex said resilient member in a direction towards the inside of tubular portion.

8. A dispenser adapted to removably accommodate a roll of self adhesive tape; comprising, a shell embodying a bottom wall adapted to be seated on a supporting surface and having a forwardly arranged front wall extending upwardly relative to said bottom wall and merged therewith, said shell having one side wall only, said side wall being substantially normal to said bottom wall and said front wall and integral with both of said last mentioned walls, a tubular portion substantially normal to said side wall and extending transversely of and within said shell and spaced from said bottom wall and having its inner end merged with said side wall and having a free unsupported outer end, said tubular portion having spaced slits leading to and interrupting said outer end to define a resilient member, said tubular portion adapted to rotatably support said roll and said resilient member having a lip projecting radially outwardly to disengageably cooperate with said roll to removably hold the latter on said tubular portion and contiguous to said side wall, and a ledge at the top of said front wall having a posterior portion to which tape unwound from said roll may be adhesively secured and having an anterior toothed portion to facilitate severing of said tape when unwound from said roll, said shell having an open side face extending across the length and height of said shell and disposed opposite to said side wall for convenient insertion of said roll into said shell and concomitantly on said tubular portion pursuant to automatic actuation of said lip by said roll to flex said resilient member in a direction towards the inside of said tubular portion.

9. A dispenser adapted to removably accommodate a roll of self adhesive tape; comprising, an open one piece shell embodying a bottom wall

adapted to be seated on a supporting surface and having a forwardly arranged front wall extending upwardly relative to said bottom wall and merged therewith, said shell having one side wall only, said side wall being substantially normal to said bottom wall and said front wall and integral with both of said last mentioned walls, a cylindrical tubular portion substantially normal to said side wall and extending transversely of and within said shell and spaced from said bottom wall and having its inner end merged with said side wall and having a free unsupported outer end, said tubular portion having circumferentially spaced slits leading to and interrupting said outer end to define a resilient member, said tubular portion adapted to rotatably support said roll and said resilient member having a lip projecting radially outwardly to disengageably cooperate with said roll to removably hold the latter on said tubular portion and contiguous to said side wall, and a ledge at the top of said front wall having a posterior portion to which tape unwound from said roll may be adhesively secured and having an anterior toothed portion to facili-
